UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed July 31, 1925. Serial No. 47,269.

To all whom it may concern:

Be it known that I, FRED M. SLATER, a citizen of the United States, and a resident of Easton, in the county of Northampton and State of Pennsylvania, have invented a certain Double-Drum Hoist, of which the following is a specification, accompanied by drawings.

This invention relates to double drum hoists in which one drum or the other is automatically connected to the drum shaft in accordance with the direction of rotation of the reversible motor furnishing power for the hoist.

15 The objects of the invention are to enable the alternate driving connection and release of one drum or the other, to be automatically controlled by the hand operated reversing device which controls the starting, stopping and direction of rotation of the motor, and to effect this automatic control in a cheap and simple manner, without complication of parts.

Further objects of the invention will 25 hereinafter appear and the invention consists of the features of construction, combinations of elements, and arrangement of parts hereinafter more fully described in this specification, and defined in the appended claims, as illustrated in the accompanying drawings, in which—

Figure 1 is an elevation partly in longitudinal section of so much of a hoist as will serve to illustrate the invention.

35 Figure 2 is a transverse sectional view on the line 2—2 of Figure 1 looking in the direction of the arrows, and

Figure 3 is an enlarged detail transverse sectional view taken through the throttle valve on the line 3—3 of Figure 1 looking 40 in the direction of the arrows.

Referring to the drawings, the main frame A is provided with side frames B and C to one of which, as for instance, the 45 side frame B may be connected any suitable motor D, as for instance, a fluid actuated motor, or an electric motor, or a motor of some other type. In a double drum hoist, like that indicated in the drawings, the 50 motor D is preferably reversible and is controlled by a suitable hand operated device, which in the case of a fluid actuated motor, may be a throttle lever E connected to a reversing valve F shown in detail in 55 Figure 3.

The motor is connected in any suitable manner (not shown) to operate a drum shaft G and two drums H and J are rotatably mounted relatively to the drum shaft G. In this instance, the drum shaft G is 60 provided with a sleeve K suitably keyed thereto as by means of the key L so that the shaft and sleeve rotate together. The drum H, as shown, rotates upon the sleeve K while the drum J rotates upon the main 65 portion of the shaft G. Suitably keyed to the sleeve K between the drums H and J as by means of the key L' but slidably longitudinally upon said sleeve K is a main driver O preferably in the form of a head 70 or disk, having clutch teeth P.

The drums H and J are provided with drum drivers in the form of clutch jaws Q and R with which the clutch teeth P on the main driver O cooperate in the operation of 75 the device. By moving the main driver O into engagement with one or the other of the drum drivers Q and R one drum or the other is connected to be driven by the drum shaft in accordance with the direction of 80 rotation of the motor D.

In accordance with this invention, means are provided controlled by the manipulation of the hand operated device E for actuating the drum driver O into engagement with one drum or the other, and for this purpose I have shown as a suitable form of apparatus, a fluid pressure cylinder S mounted on the frame A having the piston T controlled by pressure fluid, as for 85 instance, compressed air supplied to the inlet supply opening U of the valve chest V and controlled by the valve F. Suitable operative connections are provided between the controlling piston T and the main 90 driver O so that reciprocation of the piston in the cylinder S moves the main driver into engagement with one drum or the other.

In this instance, the valve F in the valve 100 chest V is provided with a rack W engaging a segment X operated by the lever E and springs Y and Z are provided in the valve chest at each end of the valve to automatically return the valve to neutral position when the lever E is released. In the position of the valve shown in Figure 3 pressure fluid admitted at the inlet U 105 passes to the motor through the passage a and the exhaust from the motor passes to 110

atmosphere from the valve chamber *b*. Pressure fluid also passes through the ports *c* in the valve and the passage *d* through the motor casing and frame of the machine 5 to the cylinder *S* to force the piston *T* forwardly and move the main driver *O* into engagement with the drum *J* as shown in Figure 1. The reverse movement of the 10 valve *F* will open the passage *d* to atmosphere through the valve chest chamber *b* and admit pressure fluid through the valve openings *e* and the passage *f* to the opposite side of the piston *T* in the cylinder *S* in which case the piston will be retracted and the drum *H* will be engaged with the main 15 driver *O*.

Any suitable means may be provided for connecting the piston *T* to the main driver and in this instance the piston rod *g* is pivotally connected to an arm *h* which is fast to a vertical rod *j* carried in the bracket *k* and provided at its upper end with a yoke *o* secured rigidly thereto as by means of the set screw *p* so that the yoke turns or rocks 20 as the rod *j* is rotated about its longitudinal axis. The yoke *o* carries pins *q* engaging a groove *r* in the main driver *O* so that the main driver is free to rotate with the drum shaft. 25

In the operation of the device, let it be assumed that the reversing valve *F* for the motor has been moved to the position as indicated in Figure 3 in which case, as described, pressure fluid will be admitted to 30 drive the motor in one direction and the fluid will also be admitted through the passage *d* behind the piston *T* so that the piston will have been moved forward in its cylinder and the vertical rod *j* will have 35 been rotated about its longitudinal axis to rock the yoke *o* and carry the main driver into engagement with the drum *J*. The drum *J* will then be rotated by the motor and will become the 40 haulage drum while the drum *H* is loose on the drum shaft and becomes the tail rope drum. By throwing the throttle lever *E* to the opposite position from that indicated in Figure 3, to reverse the motor, the 45 connections for the controlling cylinder *S* are reversed and the main driver will obviously be moved to its opposite position to connect the drum *H* and release the drum *J* in which 50 case the drum *H* becomes the haulage drum and the opposite drum the tail rope drum. 55

Obviously, when the controlling handle *E*

is in neutral or central position, the supply of pressure fluid is shut off to both the motor and the controlling cylinder *S*. Furthermore, although I have not shown reduction gearing between the drum shaft *G* and the main driver *O* it is to be understood that such provision of reduction gearing may be made as desired, but if the driving motor is of sufficiently low speed 60 no reduction gearing is necessary. 65

I claim:

1. In a double drum hoist, the combination of a drum shaft, two drums rotatable relatively thereto, a reversible motor operatively connected to drive said shaft, a main driver rotated by the drum shaft and slidable into engagement with one drum or the other, a hand operated controlling device for the motor, and means controlled by 70 said hand operated controlling device for automatically actuating said main driver into engagement with one drum or the other in accordance with the direction of rotation of the motor. 80

2. In a double drum hoist, the combination of a drum shaft, two drums rotatable relatively thereto, a reversible fluid actuated motor operatively connected to drive said shaft, a main driver rotated by the 75 drum shaft and slidable into engagement with one drum or the other, a hand operated controlling device for the motor, and fluid actuated means controlled by said hand operated controlling device for automatically actuating said main driver into engagement with one drum or the other in accordance with the direction of rotation of the motor. 85

3. In a double drum hoist, the combination of a drum shaft, two drums rotatable relatively thereto, a reversible fluid actuated motor operatively connected to drive said shaft, a main driver located between the drums and rotated by the drum shaft, drum drivers carried by the drums, fluid actuated means for causing the main driver to engage one or the other of the drum drivers, a reversing throttle for the motor, and connections controlled by said throttle for automatically controlling the fluid actuated means in accordance with the direction of rotation of the motor. 95 100 105

In testimony whereof I have signed this specification.

FRED M. SLATER.
